DESIGN FOR LEATHER

Paul Dornbusch, Crefeld, Germany, assignor to
R. Neumann & Company, Hoboken, N. J., a
corporation of New Jersey

Application June 5, 1935, Serial No. 57,157

Term of patent 7 years

To all whom it may concern:

Be it known that I, Paul Dornbusch, a citizen of Germany, residing at Industrie Str. 242, Crefeld, Germany, have invented a new, original, and ornamental Design for Leather, of which the following is a specification, reference being had to the accompanying drawing, forming a part thereof.

The figure of the drawing is a perspective view

of a piece of leather embodying my design, slightly enlarged, consisting of parallel chains of irregularly shaped triangles, joined together and resulting in a slightly wavy design.

I claim:—

The ornamental design for leather substantially as shown and described.

PAUL DORNBUSCH.
